CARTON STACKING BRACKET FOR PALLETS OR THE LIKE

Robert Lee Griffith, 501 Russell St.,
Covington, Ky. 41011

Filed Aug. 21, 1969, Ser. No. 18,794

Term of patent 14 years

Int. Cl. D8—03

U.S. Cl. D8—233

FIG. 1 is a side perspective view of a carton stacking bracket for pallets or the like showing my new design; FIG. 2 is a top plan view thereof;

FIG. 3 is a side elevational view thereof; and

FIG. 4 is a rear elevational view thereof.

I claim:

The ornamental design for carton stacking bracket for pallets or the like, as shown.
